TRAVEL CASE

Irwin W. Rosenthal, New Orleans, La.

Application November 12, 1940, Serial No. 365,350

1 Claim. (Cl. 223—71)

This invention relates to luggage, and has for its primary object the provision of a travel case of such length and breadth dimensions that it is large enough to receive a man's suit draped on a clothes hanger, folded once transversely, and without resorting to wrinkle-producing expedients to get it into the case, such as crowding, constricting or folding over lateral portions of the suit, or in any way disturbing the freely assumed suspended disposition of the suit.

A travel case of such size, conventionally constructed would be inordinately heavy, and so another object of the invention is to construct the case of covering material so light as to be non-self-shape-sustaining, necessitating the employment of a frame providing rigid shape-defining corner edge members.

A further object of the invention is to provide an apparel frame preferably shaped to fit about the inner periphery of the travel case, carrying a clothes hanger upon which the suit is draped preliminary to its being placed into the travel case, and which by inversion of the frame is folded once transversely without disturbing the smooth naturally assumed attitude of the suit, said frame being employed in combination with flatly disposed transverse retaining means on opposite sides of the frame for holding the once-folded suit in position upon the frame.

Still another object of the invention is to provide an apparel frame of the type described, in combination with auxiliary hanger bars for women's apparel, which when used in plurality may be nested, and which permit both men's and women's garments to be initially suspended, then folded over about the frame by inverting it, then held in once-folded position by the transverse retaining means, after which the frame with the garments may be put into the travel case or removed therefrom without the risk of disturbing the smooth and correct arrangement of the apparel.

Other objects of the invention will appear as the following description of a preferred and practical embodiment thereof proceeds.

In the drawings which accompany and form a part of the following specification, and throughout the several figures of which the same characters of reference have been employed to designate identical parts:

Figure 1 is a perspective view of a travel case embodying the principles of the invention;

Figure 2 is a transverse section through the case, the parts being in closed position;

Figure 3 is a perspective view of the self-shape-sustaining frame;

Figure 4 is a perspective view of the clothes frame showing a coat in its normal suspended position;

Figure 5 is a perspective view of the clothes frame in inverted position showing the coat automatically once-folded, and with the retaining means in place;

Figure 6 is a perspective view of the clothes frame showing the auxiliary hanger bars with a skirt in suspended position on one of said bars;

Figure 7 is a perspective view of the hanger bars, and showing a woman's dress draped on one bar, preparatory to inverting the frame;

Figure 8 is a view similar to Figure 6, showing the clothes frame in inverted position, the skirt automatically once-folded, and the retaining means in place.

One of the objections to a conventional travel case is that it is so sized and shaped that it is impossible to pack a man's suit therein, without having to fold or otherwise constrict it in such a manner as to make it fit within the meager dimensions of the case. A suit thus packed invariably has to be repressed before being fit to wear.

The travel case of the present invention is made of such size as to amply receive the suit in the same form in which it automatically drapes itself when freely suspended upon a clothes hanger excepting that it is once folded transversely, the folding being accomplished in such a manner as to avoid disturbing the natural hang or position of the suit.

The minimum size of the travel case of the present invention is critical as regards the suit or other apparel which it is designed to contain, but if it is designed for children's clothing it may, of course, be made of smaller size than if designed for the clothing of an adult, and still be within the scope of the invention.

In Figure 1, I have shown a travel case consisting of the two parallelepipedal compartments 1 and 2, which as shown are similar in length and breadth dimensions and in general construction, each comprising a closed bottom 3 and 4, closed sides 5, 6, and 7, 8, respectively, and the respective closed ends 9, 10, and 11, 12.

It will be understood that in general this travel case will be larger than the conventional travel case, for the reason above set forth, and that if constructed conventionally, it would be inconveniently heavy. Consequently, the inventive concept involves a construction characterized by

maximum lightness in weight. With this end in view the sides, ends and bottom of each of the compartments are covered with sheet material 13, which is so thin and flexible as in itself to be non-self-shape-sustaining. Consequently, the shape of the compartments must be defined and maintained by a light rigid skeletal framework. As shown, each of the compartments includes a pair of spaced parallel hollow frame members 14 and 15 defining the shape of the tops and bottoms of said compartments and which spaced rectangular frame members are joined by the perpendicular struts 16 and 17. The rectangular frame members and struts are preferably of metallic rod construction, the struts being welded to the frame members. Inasmuch as the sheet covering material is non-self-shape-sustaining, it is essential that certain of the struts, specifically the struts 17, be located so as to define the corner edges 18 and 19 of the respective compartments.

The said compartments are preferably hingedly connected along adjacent top edges, as shown in Figures 1 and 2, by a bridging web of the material which covers the adjacent sides 6 and 8, and are provided with handles 20 and 20'. Each compartment is preferably provided with a separator 21 and 22, respectively, of stiff but light material, hingedly connected to the respective compartments adjacent their common hinged connection, by a fabric hinge. These separators are omitted from Figure 1, for the purpose of avoiding obscuring the disclosure of the interior of the compartment. The case is closed by a slide fastener, the hooks 43 of which extend around the edges of both compartments at the front, sides and a little way around the back at both sides, as shown. A travel case made according to the above specification may be made of much larger size than the conventional travel case and yet be of equal lightness in weight, or even lighter.

The travel case is preferably furnished with a clothes frame 23, which may be of any suitable construction, but which as shown and preferred, is made from a continuous metallic rod shaped to fit about the periphery within the travel case. Said rod comprises the top and bottom bars 24 and 25 and the connecting end bars 26 and 27. The clothes frame is as wide, between the end bars, as the width of the suit in its condition of free suspension, while the height of the clothes frame between the top and bottom bars is sufficient to fully receive the suit when once folded on both sides of the clothes frame. A clothes hanger 28, which may be of ordinary shape and construction, is attached to the top bar 24 by means such as the strap 29, and normally hangs in the plane of the clothes frame and within the bounds thereof. To operate this clothes frame, the coat or suit is first suspended upon the clothes hanger, as shown in Figure 4, and then the clothes frame is inverted to the position shown in Figure 5, thus once folding the garment about the clothes frame and without disturbing its condition of smooth and correct arrangement.

For retaining the garment in once-folded position upon the clothes frame, I have provided the retaining means 30 and 31 which are preferably made of lengths of webbing 32 and which webbing may be of elastic nature. At the ends of the lengths of webbing are the hooked elements 33 adapted to embrace the end bars 26 and 27 of the clothes frame. After the garment has been once-folded about the frame, the re-

taining members 30 and 31 are put in place, one on each side, and snapped about the end bars, thus holding the apparel against displacement so that the clothes frame with the apparel mounted thereupon may be inserted into the travel case or removed therefrom and placed in a bureau drawer, for example.

Inasmuch as one of the objects of the invention is to provide a travel case which at one and the same time may conveniently receive women's as well as men's garments, I provide the auxiliary hanger bars 34 and 35, as shown in Figures 6, 7 and 8. Each of these hanger bars is preferably formed, as shown in Figure 7, comprising a transverse portion 35 with angularly disposed ends 36 and 37, said ends each terminating in a hook 38. The hooked ends of the hanger bars are slipped over the top bar 24 of the clothes frame.

In order to prevent inadvertent or accidental slippage of the hanger bars laterally from the clothes frame, I have provided the latter with the upstanding bent ears 39 and 40, forming end lugs at the ends of the top bar 24. In employing the hanger bar for women's clothing, the garment, if short, for example a skirt, may be suspended therefrom in any suitable manner as by means of the clothes pins 41. If long, as in the case of a waist and skirt ensemble, it is first draped across the hanger bar at the waistline, as shown in Figure 7. In either instance, the clothes frame is then inverted, the garment occupying the position shown at 42 in Figure 8, the garment being thus once-folded. The retaining means 30 and 31 are employed to keep the garment in place relative to the clothes frame.

It will be understood, of course, that the men's and women's garments may be suspended upon the respective clothes hanger and auxiliary hanger bar on the same clothes frame, and the latter inverted, once-folding both garments at the same time.

Figures 6 and 8 show a plurality of hanger bars, one being nested within the angular end portions of the other, so that more than one woman's garment may be packed at one time.

It will be understood that while in its preferred embodiment the clothes frame is an element in combination with the travel case shown in Figures 1, 2 and 3, it has a separate utility of its own, as it may be removed from the travel case with the apparel correctly and securely arranged thereupon and transferred to a bureau drawer where it may be kept indefinitely, according to convenience. The apparel is removed from the clothes frame by holding the latter in inverted position, removing the retaining bands 30 and 31 and then reverting the frame, whereupon the clothes will again be suspended, respectively, from the clothes hanger and hanger bar or bars and be in the same original condition of fresh press as when first suspended preparatory to packing.

While I have in the above description disclosed what I believe to be a preferred and practical embodiment of the invention, it will be understood to those skilled in the art that the details of construction and the arrangement of parts as shown and described, are largely by way of example and not to be construed as limiting the scope of the invention, which is defined in the claim.

What I claim as my invention is:

Apparel frame of such size as adapts it to fit within a hand travel case and therefore being

shorter than a skirt or coat, comprising a continuous rectangular member bent from rod material having parallel top and bottom bars and parallel side bars and being the full width of a skirt or coat when in naturally draped position, said top bar having upstanding ears at the ends, a plurality of hanger bars adapted to suspend articles of apparel, the latter being automatically infolded about said apparel frame by inversion of the latter, each of said bars comprising a transverse portion with angularly disposed ends, each end terminating in a hook, one of said hanger bars being of such width that its hooks may engage the top bar of the frame ad-

10 jacent the upstanding ears whereby lateral movement of said hanger is prevented, successive hanger bars being of successively decreasing width and height whereby the hanger bars may be suspended from the top bar of the frame and nest one within the other and hang in a common plane, said hanger bars being held against detachment from said frame by the tension of the infolded apparel, and elastic straps bridging said frame one on each side of the apparel, having means at their ends engaging the opposite side bars and shiftable upwardly or downwardly along said bars.

IRWIN W. ROSENTHAL.
